CABANA

Sam H. Vuncannon, Miami, Fla.

Application July 2, 1954, Serial No. 31,268

Term of patent 14 years

(Cl. D88—3)

Fig. 1.

Fig. 2.

To all whom it may concern:

Be it known that I, Sam H. Vuncannon, a citizen of the United States, residing at Miami, Fla., have invented a new, original, and ornamental Design for a Cabana, of which the following is a specification, reference being had to the accompanying drawing, forming a part thereof.

I claim:

The ornamental design for a cabana, as shown.
